UNITED STATES PATENT OFFICE.

JOHN WOODWARD AND ROBERT ANDERSON, OF OIL SPRINGS, ONTARIO,
CANADA.

PUMP.

SPECIFICATION forming part of Letters Patent No. 388,943, dated September 4, 1883.

Application filed April 27, 1887. Serial No. 236,282. (No model.) Patented in Canada December 13, 1886, No. 25,551.

To all whom it may concern:

Be it known that we, JOHN WOODWARD and ROBERT ANDERSON, citizens of Canada, residing at Oil Springs, in the county of Lambton 5 and Province of Ontario, Canada, have invented certain new and useful Improvements in Pumps, (for which we have obtained a patent in Canada, since then improved, No. 25,551, bearing date December 13, 1886,) of which the 10 following is a specification.

The invention relates particularly to deep-well plunger-pumps; and it consists, first, in a loose gravitating sleeve encircling the piston-rod and closing the upper end of the barrel, so 15 that it may rise freely from its seat.

It also consists in the peculiar construction and combination of parts at the lower end of the barrel, as hereinafter described, and specified in the claims.

20 Figure 1 is a sectional elevation of the pump. Fig. 2 is a plan view of the steadyng-collar. Fig. 3 is a sectional plan view on line *x x*. Fig. 4 is a plan of the working-barrel seat. Fig. 5 is an enlarged outside view of the plunger.

25 That part of the pump which is shown in the drawings, and which contains our improvements, is, when in use, submerged in the liquid, and is supported by the trunk-pipe of the pump, which reaches down from the ground- 30 surface and is screwed into the top end of the shell A, which is simply a piece of plain pipe. B is the working-barrel seat. It is provided with a central polygonal flange, *a'*, by which it is turned, and both above and below this 35 flange it is screw-threaded, so as to allow of its being screwed both into the bottom end of the shell A and into the top end of the strainer C. The working-barrel D stands in the shell-tube A, has its bottom end screwed into the 40 barrel-seat B and its top end steadied by the steadyng-collar E, which has the arms *b'* reaching out against the shell. The pump rod F works through a loose-fitting sleeve, *c'*, which rests on the top of the working-barrel and prevents scales or dirt from entering the working- 45 barrel. A ball-valve, G, is fixed in the lower end of the working-barrel, and a similar valve, H, is attached to the pump rod F. Vent-holes *d'* are made in the working-barrel, near its up- 50 per end, for the purpose of allowing the dis-

charge of the oil from the working-barrel without lifting the sleeve *c'*, except under great pressure. The strainer C is a plain tube screwed on the barrel-seat B, as shown in Fig. 1, and has its lower end closed. It serves as a depository 55 for any sediment that may be drawn into it. A drop-tube, I, is placed in the strainer, screwed, as shown, into the barrel-seat B, and extends below the induction-openings *e'*, so that as the oil enters through these openings it is obliged to 60 descend some distance before being drawn into the drop-tube I. This downward current helps to throw any sediment to the bottom of the strainer.

Our improvement in the ball-valves consists 65 in making the shoulder against which the bottom edge of the ball-cage is held movable on the valve-seat pipe *g'*, which may be thereby set at any desired height in the ball-cage *h'*, and the play of the ball increased or diminished to suit the kind of work the pump may 70 be required to do.

The valve-ball *i'* rests on the top end of the pipe *g'*, which constitutes the valve's seat. The cage *h'* is screwed on the outside of the pipe 75 *g'*, and is turned down until the inside height of the cage is such that the ball in it will be allowed only the proper amount of vertical play. The lower edge of the cage is brought into close contact with the shoulder or top edge 80 of the collar *j'*, which terminates its downward motion on the pipe *g'*.

In this class of valves as heretofore made the collar *j'* has been either formed of a piece with or rigidly attached to the valve-seat pipe *g'*, 85 which necessitated the cutting down of the collar when the lowering of the cage on the pipe *g'* became necessary through the wearing down of the valve-ball seat. Our invention renders this cutting down unnecessary 90 by making the collar movable on the pipe. The cage and collar being similarly screwed on the pipe *g'*, may be raised or lowered together or separately, as occasion may require.

We claim as our invention in the above-described pump—

1. The combination, in a pump, of a working-barrel open at the upper end and provided with an outlet below said end, a pump-rod extending into the barrel from above, and a loose 90

gravitating sleeve embracing the piston-rod and adapted to move along the same to normally close the upper end of said barrel and open it under abnormal pressure, substantially as set forth.

2. The combination of the shell A, the strainer C, working-barrel D, drop-tube I, and the seat B, this latter having flange a' and being provided with screw-threads above and below said flange on its inner and outer faces, whereby it is adapted to screw into the shell

and strainer and over the working-barrel and drop-tube, respectively, and secure all said parts together, substantially as shown and described.

Signed at Petrolia this 16th day of April, 1887.

JOHN WOODWARD.
ROBERT ANDERSON.

In presence of—

JAMES SCHULTZ,
JAMES CAMERON.
